Specification for Design.

Patented Apr. 27, 1915.

Application filed February 1, 1915. Serial No. 5,575. Term of patent 7 years.

To all whom it may concern:

Be it known that we, HENRIETTA V. METZGER and HELEN VON HARTZ, citizens of the United States, residing at Cleveland, in the county of Cuyahoga and State of Ohio, have invented a new, original, and ornamental Design for Jackets, of which the following is a specification, reference being had to the accompanying drawing, forming part hereof, wherein the figure represents a front elevation of a jacket exhibiting our new design and having one of its sides folded to one side.

I claim:

The ornamental design for a jacket as shown.

HENRIETTA V. METZGER.
HELEN VON HARTZ.
